GASIFICATION APPARATUS

Filed July 30, 1929

UNITED STATES PATENT OFFICE

WILLIAM B. CHAPMAN, OF JACKSON HEIGHTS, NEW YORK

GASIFICATION APPARATUS

Application filed July 30, 1929. Serial No. 382,222.

The invention relates to the low temperature carbonization or distillation of coal or other solid fuel containing volatile hydrocarbons as a preliminary step employed in conjunction with the complete combustion of fuel, the final step preferably being the manufacture of producer gas which gas, if desired, may be immediately burned after leaving the firebed, for boiler heating or other analogous purposes, and for providing additional heat for accelerating said preliminary step.

One object of the invention is to enable the low temperature distillation of fuel to be carried out under improved heating conditions, the invention making it possible when its features are utilized in full, to obtain gas by low temperature distillation which is rich enough to go into city mains, and the low temperature distillation being carried out in a zone where- 20 in the gas and heat made available by the final step of complete gasification are efficiently utilized. Gases distilled off at low temperatures may also be obtained which are substantially undiluted with lean or inert gases while 25 simultaneously the fuel is completely gasified leaving no coke residue for which a market would have to be found. Further objects and advantages of the invention will be in part obvious and in part specifically pointed out in 30 the description hereinafter contained which, taken in conjunction with the accompanying drawing, discloses an apparatus adapted to be operated in accordance with the invention. This disclosure, however, should be understood as being merely illustrative of the principles of the invention. In the drawing—

Fig. 1 is a vertical sectional view taken through an apparatus adapted to be operated in accordance with the invention.

Fig. 2 is a section taken on line 2—2 of Fig. 1.

In accordance with the present invention the preparatory step of low temperature distillation is carried out in a preheating or distillation zone of a firebed substantially concentric with the combustion zone wherein the final step of complete gasification takes place, whereby the coal fed to the first zone is heated uniformly, by the second firebed zone and the gas produced in the latter. Preferably the

fresh coal is fed into the central zone of a firebed, in such manner that, after the preparatory step of low temperature distillation has taken place therein, the coal then passes to an annular zone of the firebed surrounding the first mentioned zone and in close contact therewith, making it possible to draw off the low temperature distillates from the central zone of the firebed without substantially mixing therewith the producer gas generated in the surrounding zone of the firebed. I prefer also to employ an underfeed of coal, and take off the low temperature distillates downwardly from the central distillation zone of the firebed, as is hereinafter described in greater detail. It should be understood also that the above mentioned firebed zones may be employed in installations wherein the final step of gasification involves complete combustion of the fuel in the firebed, although, as above stated, particularly where the low temperature distillate is desired to be obtained substantially free from dilution, I prefer to employ a deep firebed which will generate 60 producer gas. But whether the combustion be only partial, thus making producer gas, or complete, no coke residue is contemplated.

In the apparatus illustrated in Fig. 1, the firebed enclosing walls 1, which may have a water-cooled lower section 2, are supported by a suitable number of pedestals 3, and a rotatable pan 4 having gear teeth 5 for engagement with any suitable driving gear or the like (not shown) underlies the firebed, the pan being carried by the rollers 6 extending from pedestals 3. A hollow skirt or base 7 depends from the side walls into pan 4 in such manner as to form a water-seal with the latter, and as shown air is supplied to the firebed through a pipe 8 leading to an annular air distributing chamber 9 within skirt 7, the air passing into the lower portion of the firebed through a suitable number of narrow grate openings 10 and 11 in the inner wall of skirt 7. The conical shape of the base or skirt 7 provides a stationary support beneath a sufficient part of the firebed to prevent the latter from turning around with pan 4.

Fuel is fed into the central or distillation zone of the firebed from hopper 12 by a hori-

zontal feed screw 13 which delivers the fuel to the lower end of a vertical feed screw 18 operating within a stationary casing 16, supported by a suitable number of brackets 17, the helical blade or screw 18 serving to feed fuel upwardly into the outwardly flaring hopper 19, which constitutes a partition separating the central or distillation zone of the firebed within which the fuel is traveling upwardly, from the peripheral or combustion zone of the firebed into which the fuel progressively passes and travels downwardly until the ash is ejected from pan 4 through the water-seal and over the edge of the pan in any suitable manner as by a conventional ash plow (not illustrated). Hopper 19 is constructed either of special heat resisting metal as shown, or it may be water cooled.

A suitable number of firebed agitating arms 20 may be carried by the pan 4 and rotated through the ashes in the bottom portion of the firebed to break up clinkers and close up blow-holes and assist in maintaining uniform conditions of fuel consumption in said peripheral zone, and also assist in stroking the ash downwardly to pan 4 and through the water seal, the firebed as a whole being held against rotation by the sidewalls 1, skirt 7, casing 16 and hopper 19.

30 The hopper 19 guides fuel outwardly to some extent, and tends to prevent producer gas from readily reaching the outlet for the low temperature distillates.

As the incoming fuel travels through the firebed zone defined by hopper 19, casing 16 and feed screw pipe 14, such fuel will be subjected to the heat of the surrounding firebed zone, in which latter the consumption of the fuel is completed by the air blast from chamber 9, this relation of parts serving to heat the incoming fuel evenly all the way around the walls of casing 16 and hopper 19 and in addition the gases issuing from the peripheral zone of the firebed are free to play over or be burned over the top surface of the fuel supported by casing 16 and hopper 19, low temperature distillates being thereby driven off from the fresh fuel before the latter passes to the peripheral zone of the firebed. Usually distillates up to about 950° F. will be driven off in the above manner, after which the residual fuel passes to the peripheral zone of the firebed, and as above stated I prefer to maintain a deep firebed in such peripheral zone, thereby making gas of the producer gas type in the latter. Producer gas so obtained, it should be understood, may be either immediately burned in admixture with secondary air thereby increasing the low temperature gasifying capacity of the equipment, or conducted off from the space above the surface of the firebed, as desired.

The low temperature distillates driven off during the first stage of gasification which takes place within the central zone of the

firebed as above described, may be separately drawn off into the pipe or hollow shaft 14, through ports 21 disposed in the wake of travel of the helical blade 18, so that the rotation of said blade keeps the fuel away from said ports and thus prevents them from becoming clogged. The low temperature distillates then are conducted away preferably through an off-take pipe 22 leading from the interior of the feed screw member 14 and preferably forming a liquid-sealed connection with the latter, the liquid being held in container 23 underlying member 14. From thence the gas is piped to the cooling and cleaning apparatus.

The fuel delivered at the top of vertical screw 18 is preferably directed upwardly to some extent by an inclined blade 24 rotating with member 14 and provided with a scraper 25 acting on the surface of hopper 19 to clean the same and to keep the fuel moving outward. While for convenience the entire fuel bed is referred to herein as a "firebed", it should be understood that actual (partial) combustion of the fuel is limited to the outer annular zone to which oxygen is supplied.

I prefer also to provide a further rotatable agitating member 26 operating in the top surface of the firebed to stroke the fuel outwardly, and level out the top surface of the firebed to some extent and also to prevent blow-holes and to maintain as far as possible uniform density throughout the contents of the central distillation zone. The prevention of channels in the central zone is of the utmost importance, since channels would cause the rich gases in the central zone to be diluted by the drawing in of a portion of the low value gases surrounding said zone. The need for adequate agitation is therefore apparent. In the illustrated form of the invention, this agitating member 26 rotates concentrically within fuel feed member 14 although at a different speed and has a plate 27 which overlies and closes the bearing in the top of the member 14 and is scraped clean by the up-stroking blade 24, the agitating member 26 being driven by a gear 28 fixed to the lower end of its stem 29, said gear 28 being engaged by a driving pinion 28a. The fuel feed member 14 is illustrated as rotated by a similar gear 30 connected to its lower portion, and engaged by a driving pinion 31.

If desired, a certain amount of low grade oil or tar may be mixed in with the fuel fed to the apparatus, particularly if the latter is desired to be enriched or to have a large overload capacity, low temperature distillates being obtained therefrom in the same manner as above described, and the residuum passing along with the fuel to the second stage of gasification.

While the invention has been described as carried out by a specific apparatus, it should be understood that many changes may be

made without departing from its essential features as set forth in the appended claims.

I claim:

1. An apparatus for gasifying fuel, having firebed enclosing walls substantially symmetrically disposed with regard to a central vertical axis means for feeding air to an annular zone in the firebed, a fuel underfeed device operating substantially concentrically with said axis for feeding fuel to the central portion of the firebed, and an off-take pipe for low temperature distillates enclosed by said fuel feeding device.
2. An apparatus for gasifying fuel, having firebed enclosing walls substantially symmetrically disposed with regard to a central vertical axis, means for feeding air to an annular zone in the firebed, a fuel underfeed device operating substantially concentrically with said axis for feeding fuel to the central portion of the firebed, and an off-take pipe for low temperature distillates, also disposed substantially concentrically with regard to such axis, and leading downwardly from the central portion of the firebed.
3. An apparatus for gasifying fuel, having firebed enclosing walls substantially symmetrically disposed with regard to a central vertical axis, means for feeding air to an annular zone in the firebed, a fuel underfeed device operating substantially concentrically with said axis for feeding fuel to the central portion of the firebed, and an off-take pipe for low temperature distillates also disposed substantially concentrically with regard to such axis and leading downwardly from the central portion of the firebed, said fuel feeding device having a fuel agitating member operating adjacent said off-take pipe.

device operating substantially concentrically with said axis for feeding fuel to the central portion of the firebed, and an off-take pipe for low temperature distillates enclosed by said fuel feeding device.

3. An apparatus for gasifying fuel, having firebed enclosing walls substantially symmetrically disposed with regard to a central vertical axis, means for feeding air to an annular zone in the firebed, a fuel underfeed device operating substantially concentrically with said axis for feeding fuel to the central portion of the firebed, and an off-take pipe for low temperature distillates also disposed substantially concentrically with regard to such axis and leading downwardly from the central portion of the firebed, said fuel feeding device having a fuel agitating member operating adjacent said off-take pipe.
